DESIGN FOR A DOLL BABY NOVELTY

A Lester Gaba, New York, N. Y., assignor to Kerk Guild, Inc., Utica, N. Y., a corporation of New York

Application November 28, 1934, Serial No. 54,188

Term of patent 3½ years

To all whom it may concern:

Be it known that I, A Lester Gaba, a citizen of the United States, residing at 237 E. 20th Street, New York, county of New York, and State of New York, have invented a new, original, and ornamental Design for a Doll Baby Novelty, of which the following is a specification, reference being had to the accompanying drawing, forming part thereof.

In the drawing:

Fig. 1 is a front view of a doll baby novelty showing the new design.

Fig. 2 is a horizontal sectional view on line 2—2 of Fig. 1.

Fig. 3 is a vertical transverse sectional view on line 3—3 of Fig. 1.

The present design, as shown, presents as its dominant or characteristic feature five separate, similar dolls partially enclosed within the five similar pockets of a flexible carrying case, representative of "quintuplets" in bed.

I claim:

The ornamental design for a doll baby novelty as shown and described.

A LESTER GABA.
